DIE AND PUNCH RETAINER DEVICE

Richard Chaney, Dayton, Ohio, assignor to The Sheffield Corporation, Dayton, Ohio, a corporation of Ohio

Application February 3, 1947, Serial No. 726,113

14 Claims. (Cl. 279—76)

1

This invention relates to retainer devices for demountable punches, dies and the like.

One object of the invention is the provision of a holder or retainer of this character wherein the punch or die may be positively inserted and withdrawn and, when inserted, will be held firmly and in a predetermined definite position.

Another object is the provision of a retainer having a screw engageable with the shank of the punch or die to positively withdraw the shank, and an additional locking device which also normally acts to prevent withdrawal during operation.

Another object is the provision of a retainer device having a locking roller which normally has line contact with the shank of the punch or die and which acts to definitely locate the shank with respect to the retainer block, the roller being releasable from the shank by means of a screw that is effective to positively withdraw the shank.

Another object is the provision in a retainer device of this character of a punch or die having a shank provided with a cylindrical surface slidably engageable in the retainer block and having an annularly restricted portion that has straight ribs that may be engaged by a screw thread, a flat gripping surface being provided between the end of the shank and the inclined ribs for engagement with a retaining roller.

Other objects and advantages of the invention will be apparent from the following description, the appended claims and the accompanying drawing, in which

Fig. 1 is a sectional view through the retainer centrally through the shank of the punch or die as indicated by the line 1—1 of Fig. 2;

Fig. 2 is a plan view of the retainer block as viewed on line 2—2 of Fig. 1 with the tool shank and its holding parts removed;

Fig. 3 is an end view of the tool shank;

Fig. 4 is a side elevation of the tool shank;

Fig. 5 is a sectional view through the retainer device centrally through the tool showing the position of the parts the instant withdrawal movement begins; and

Fig. 6 is a view of the retaining roller.

Referring more particularly to the drawing in which a preferred embodiment of the invention is shown, the punch or die 10 has its shank 11 mounted with a sliding fit in a retainer block 12 which is connected to the hard back plate 13 and mounted on die shoe 14 by means of attaching screws 15 in the screw sockets 16. Dowel pins 17, arranged in dowel openings 18, locate the retainer block on the die shoe.

2

As shown in Figs. 1 and 2, the retainer block has a cylindrical tool socket 20 in which the shank 11 fits. Intersecting or overlapping the circular tool socket is a cavity 21 the lower portion of which is a circular bore parallel to the axis of the tool shank and intersecting the tool socket and forming a seat for an operating screw 22, the lower side of the screw seat being partly closed by an apertured shoulder 23 through which the stem of a wrench can be inserted to engage the recess 24 in the lower side of the screw so that the screw can be turned in one direction or the other.

The tool shank, at a suitable distance from the upper end which engages against the back plate 13 and in a zone which extends circumferentially much less than 90 degrees, is provided with a series of ribs 25. The ribs, as shown, are of V shape, either straight across the shank or inclined in accordance with the helical angle of the screw 22. As shown in Fig. 3, 26 indicates the bottom of the rib grooves. These ribs may be very readily made by a grinding wheel of substantial diameter, provided with V-shaped ribs 25 and moved back and forth in the direction of the line 26. The tool shank may be inserted into the tool socket until the top rib 27 engages the bottom thread on the screw 22 and then when the screw is turned in the direction of the arrow shown in Fig. 5, the tool shank will be drawn into the socket, the lower end of the screw remaining in engagement with the shoulder 23. Further rotation of the screw will then be prevented when the end of the screw shank engages the back plate 13. It will also be apparent that if the screw is then rotated in the opposite direction it will tend to screw itself upwardly along the ribs of the shank but if the screw is held against upward travel its rotation will positively withdraw the tool shank, thus facilitating the removal of the shank even if the shank should break above the bottom of the retainer block.

The upper portion of the cavity 21 is elongated as shown in Fig. 2 and is inclined as shown in Fig. 1 to the axis of the tool socket, forming an inclined surface 29 having line contact with a roller 30. The inclined portion of the cavity opens into the tool socket so that when the roller is in its normal holding position, as shown in Fig. 1, it extends partly into the socket and engages against a flat gripping surface 31 on the tool shank. A spring 32 arranged above the roller bears against the back plate 13 and preferably has an extended end 33 inserted in a socket 34 in the retainer block, the lower end of

the spring engaging the top of the roller so as to yieldingly urge the roller down along the surface 29 and into engagement with the flat gripping surface 31 on the shank. This is the position of the parts as shown in Fig. 1, the screw 23 having been turned to fully insert the tool shank in the tool socket and the roller projecting into the tool socket in gripping engagement with the tool shank. The angle of inclination of the surface 29 with respect to the axis of the tool is so co-ordinated with the angle of the gripping surface 31 as to give a self-locking or wedging engagement between the tool shank, the roller and the surface 29 when a downward pull is exerted on the end of the tool itself. The tool will thus be firmly held with its end against the back plate 13 during operation by means of the roller, so that the holding action of the screw 22 need not be relied upon to prevent loosening of the tool in operation. The threads on the screw and the ribs on the tool with which the screw threads engage will thus be relieved of the strain imposed during operation. It has been found quite suitable to have the angle of inclination of the surface 29 about 18 degrees with respect to the axis of the tool and have the angle of the gripping surface 31 about 14 degrees to the axis of the tool although obviously variations may be made in this angular relationship.

When the roller is in firm engagement with both the surface 29 and the gripping surface 31, it will be apparent that rotational shifting of the tool is positively prevented. This is important where the shape of the punch or die is other than circular in order that the proper relation will be kept between the punch and the die in a cooperating die set.

The inclined flat gripping surface 31 extends far enough towards the end rib 27 so there is proper locking engagement between the roller and the tool shank, and beyond the surface 31 between it and the end rib 27 the tool shank may be flattened as indicated at 35. Between the gripping surface 31 and the end of the tool shank is a flat surface 37 which is somewhat closer to the tool axis than the base of the grooves or ribs 25 so that the end of the tool shank when inserted in the lower end of the retainer block can be moved past the threads on the screw 22 without interference with those threads. When the end of the shank is inserted and before the screw engages the ribs on the shank the roller is engaged by the beveled surface 38 at the end of the shank, or with the end portion of the flat surface 37 which is effective to automatically position the tool in an exact predetermined position or relation in the retainer and hold it against any rotational movement during operation of the screw. Rotation of the screw of course inserts the shank until the roller rides down the inclined gripping surface 31 and until the end of the tool shank abuts against the plate 13. In this position the parts are as shown in Fig. 1, there being some clearance space between the bottom of the roller and the top of the screw 22, and there being some space between the convolutions of the spring 32. Both the screw and the roller have a holding action preventing withdrawal of the tool shank at this time.

To remove the tool shank, the screw is rotated in the opposite direction and since the roller still acts to hold the tool shank the initial movement of the screw causes its axial travel along the ribs of the tool shank until it engages and retracts the roller, thus moving the roller up-

wardly to the position shown in Fig. 5, from the normal locking position shown by the dash lines. The roller is thus moved clear of the inclined gripping surface 35. The upward movement of the roller compresses the convolutions of the spring which then forms a positive stop to prevent further upward movement of the roller and thus prevent further upward travel of the screw. Continued rotation of the screw is then fully effective to create a pulling force on the tool shank and retract the shank positively even though the tool may have been broken in operation.

The action of the roller in definitely positioning the tool shank and holding it against any rotational movement permits firm engagement of the end of the tool shank with the back plate 13 due to the yielding action of the roller in locating the tool shank. This avoids the necessity of a positive key directly between the tool shank and retainer. A positive key between the tool shank and the retainer would necessarily have to be made with extreme precision in order to fit firmly without play in either the tool shank or retainer and also permit for firm engagement of the tool shank with the back plate, and these are conditions that are impractical to obtain in manufacturing operations.

As will be apparent, the parts are of simple form and construction and are capable of operation over prolonged periods of time. The ready removal of the punch or die from the forward side of the retainer block without having to remove the retainer block from the back plate or from the retainer shoe is of course a decided advantage in changing or replacing the punch or die.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A device of the character described, comprising a retainer having a tool socket for receiving the shank of a tool with a sliding fit and a cavity at one side opening into the socket, a screw in said cavity projecting radially into the socket to engage ribs on the tool shank for inserting and withdrawing the tool when the screw is rotated, said retainer having an apertured shoulder for retaining one end of the screw, and a locking member in said cavity adapted for locking engagement with a side of the shank to hold the shank against removal, said screw when rotated to withdraw the shank operating to release said locking member.

2. A device of the character described, comprising a retainer having a tool socket for receiving the shank of a tool with a sliding fit and a cavity at one side opening into the socket, a screw in said cavity projecting radially into the socket to engage ribs on the tool shank for inserting and withdrawing the tool when the screw is rotated, said retainer having an apertured shoulder for retaining one end of the screw, and a locking roll in said cavity adapted for locking engagement with a side of the shank to hold the shank against removal, said screw when rotated to withdraw the shank being movable along the ribs of the shank to release said locking roll.

3. A device of the character described, comprising a retainer having a tool socket for receiving the shank of a tool with a sliding fit and a cavity

at one side opening into the socket, a screw in said cavity projecting radially into the socket to engage ribs on the tool shank for inserting and withdrawing the tool when the screw is rotated, said retainer having a portion for retaining one end of the screw, and a spring pressed holding member in said cavity engageable with a side of the shank to position the shank against rotation, said screw having a portion for releasing the holding member when the screw is operated to withdraw the tool.

4. A device of the character described, comprising a retainer having a tool socket for receiving the shank of a tool with a sliding fit and a cavity at one side opening into the socket, a screw in said cavity parallel to the socket and projecting into the socket to engage ribs on the tool shank for inserting and withdrawing the tool when the screw is rotated, said retainer having an apertured shoulder for retaining one end of the screw, said cavity having a surface inclined from the back of the retainer toward the socket, a positioning member in said cavity engagable with a side of the shank and said inclined surface, and spring means urging said member towards the socket, said member and screw having a spaced relation when the shank is positioned so that rotation of the screw to withdraw the shank first releases the member from the shank.

5. A device of the character described, comprising a retainer having a tool socket for receiving the shank of a tool with a sliding fit and a cavity at one side opening into the socket, a screw in said cavity projecting radially into the socket to engage ribs on the tool shank for inserting and withdrawing the tool when the screw is rotated, said retainer having an apertured shoulder for retaining one end of the screw, and a locking roll having an axis extending transversely of the axis of the socket and arranged in said cavity so that its cylindrical locking surface is adapted for line contact and wedging engagement with a side of the shank to hold the shank against removal, said screw when rotated to withdraw the shank being movable along the ribs on the shank to release said locking roll from the shank.

6. A device of the character described, comprising a retainer having a tool socket for receiving the shank of a tool with a sliding fit and a cavity at one side opening into the socket, a screw in said cavity parallel to the socket and projecting into the socket to engage ribs on the tool shank for inserting and withdrawing the tool when the screw is rotated, said retainer having an apertured shoulder for retaining one end of the screw, a roll in said cavity extending transversely of the socket and adapted for line contact with a side of the shank to hold the shank in position, spring means urging the roll against the shank, said screw when rotated to withdraw the shank operating to release said roll.

7. A device of the character described, comprising a retainer block having a cylindrical tool receiving bore and a cavity providing a guide surface inclined relatively to said bore, a roller in said cavity having its axis transverse of said bore and operable along said surface with line contact therewith and projecting into said bore, spring means urging said roller towards said bore, and a screw for positively inserting and withdrawing the tool and engageable with the roller to retract it from the bore.

8. In a retainer device for demountable punch, die or like tool, a retainer block having a tool

socket for receiving the shank of a tool with a sliding fit, a tool having a shank in said socket formed with an annularly restricted series of ribs and having a flat gripping surface between

5 the ribs and the end of the shank, said retainer block having a cavity at one side of the tool socket and extending to the tool socket, means for securing the retainer to a backing plate, a screw in said cavity projecting radially into the socket and engaging the ribs on the tool shank for inserting and withdrawing the tool shank when the screw is rotated, said block having an apertured shoulder for retaining one end of the screw and providing access to the screw, a locking roller in said cavity having line contact with the gripping surface on the shank to prevent rotational and withdrawing movement of the shank, spring means urging said roller against said gripping surfaces, said screw when rotated to withdraw the shank operating to release the locking roller.

9. A tool adapted for detachable mounting in a retainer, said tool having a shank portion which throughout the major portion thereof is a plain cylindrical surface adapted for sliding movement, said cylindrical surface having an annularly restricted portion provided with ribs adapted for engagement with a screw thread to effect a longitudinal sliding movement of the tool shank, the shank of the tool having a flat gripping surface between the end of the shank and said ribs.

10. A tool adapted for detachable mounting in a retainer, said tool having a shank portion which throughout the major portion thereof is a plain cylindrical surface adapted for sliding movement, said cylindrical surface having an annularly restricted portion provided with inclined straight ribs adapted for engagement with a screw thread to effect a longitudinal sliding movement of the tool shank, the shank of the tool having a flat gripping surface extending from the end of the shank to said inclined ribs.

11. A tool adapted for detachable mounting in a retainer, comprising a shank portion which throughout the major portion thereof is a plain cylindrical surface adapted for sliding movement, said cylindrical surface having an annularly restricted portion provided with ribs adapted for engagement with a screw thread to effect a longitudinal sliding movement of the tool shank, the shank of the tool in the zone between the end of the shank and said ribs having a gripping surface of such character that transverse sections through the shank where such gripping surface is located indicate the gripping surface as a straight chordal line extending entirely across the shank.

12. A tool adapted for detachable mounting in a retainer, comprising a shank portion which throughout the major portion thereof is a plain cylindrical surface adapted for sliding movement, said cylindrical surface having an annularly restricted portion provided with ribs adapted for engagement with a screw thread to effect a longitudinal sliding movement of the tool shank, the shank of the tool having a flat gripping surface between the end of the shank and said ribs with said gripping surface extending at an angle to the axis of the shank so that the surface lies a progressive distance from the shank axis as it approaches the end of the shank.

13. A device of the character described comprising a retainer having a tool socket for receiving the shank of the tool with a sliding fit

7
a fifth foot of the shank 7 and being bushed at the end, and a cavity at one side opening into the socket, means operable from the exterior of the socket for positively moving the tool shank axially inwardly or outwardly, and additional means in said socket in general axial alignment with said first means for retaining the shank against outward movement.

14. A device of the character described comprising a retainer having a tool socket for receiving the shank of a tool with a sliding fit, 10 said retainer having a cavity at one side opening into the socket, threaded means for positively moving the shank of the tool into and out of the socket and a locking member cooperatively associated with said threaded means for holding 15 the tool in the socket.
